DRAPERY PLEAT CONSTRUCTION

Alice M. Freeman, Minneapolis, Minn.

Application June 19, 1950, Serial No. 168,958

3 Claims. (Cl. 160—348)

1

The herein disclosed invention relates to drapes and has for an object to provide means whereby pleats and particularly pleats ordinarily known as French pleats may be easily and quickly made in drapes.

Another object of the invention resides in providing a drape shaper whereby the pleats may be formed in the drapes without the use of sewing.

A still further object of the invention resides in providing a form over which the pleats are formed.

An object of the invention resides in constructing the form of bendable sheet material of a stiffness greater than that of the material from which the drape is constructed and in forming in the sheet spaced parallel bends to provide panels therebetween.

Another object of the invention resides in arranging the bends with the reentrant angles of alternate bends on opposite sides of the sheet to permit of folding the panels in accordion fashion.

A still further object of the invention resides in folding the material of the drape about the bends and panels of the form to provide panels on the drape overlying the panels on the form and to further provide fasteners extending through the panels of the drape and form to secure the parts together.

An object of the invention resides in providing a clip secured to the drape at certain of the folds thereof and to which a hanger for supporting the drape may be attached.

Another object of the invention resides in constructing the clip of sheet metal constructed with a channel in which certain of the folds of the drape may be received.

A still further object of the invention resides in constructing the clip with a hole extending across the channel thereof and into which a pin may be inserted for engagement with the folds of the drape.

In the drawings:

Fig. 1 is a perspective view of a portion of a drape illustrating the invention and showing the method of applying the same thereto.

Fig. 2 is an elevational view of a portion of a drape showing the pleats formed therein.

Fig. 3 is a sectional view taken on line 3—3 of Fig. 1 and drawn to a greater scale.

Fig. 4 is an elevational view of one of the clips of the invention.

Fig. 5 is a developed view of one of the forms of the invention.

The invention disclosed in this application includes a form constructed from a flexible material

2

having greater stiffness than the material from which the drape is constructed and which is bent along three parallel lines to form four panels. The reentrant angles formed by the outer bends are on the opposite side of the form from the reentrant angle formed by the inner bend so that the panels may be folded together in accordion fashion. The portion of the drape to be plated is formed over the form and is provided with bends and panels conforming to the bends and panels of the form. The parts are stitched together by means of wire stitches or staples at the vicinity of the pleats and by means of which the same are tied together. Operating in conjunction with the form is a clip which consists of a plate constructed of some rigid material such as aluminum, plastic, or the like, and which has a channel extending along the back of the drape and at the locality where the inner folds of the drape occur. These folds are received within said channel. The said clip has a number of transverse slots therein adapted to receive pins, which pins extend through the folds of the drape in the channel of the clip and attach the same to the clip. The clip is further provided with a hook by means of which the same may be hung on a rod or other supporting structure for the drape.

In the construction of drapes the customary practice is to form pleats at the upper portion of the drape and at the locality of the support of the same on the supporting rods for the drape. Such pleats are usually arranged in groups of three and are referred to in the art as "French" pleats. The common method of constructing such pleats requires forming the same by hand and sewing the folded portions of the fabric together. This involves considerable time and annoyance and great difficulty is encountered in making all of the pleats look exactly the same. The instant invention overcomes this objection by providing a construction whereby the pleats may be quickly and readily formed and without the painstaking required by the common method.

For the purpose of illustrating the invention a portion of a drape has been shown which is designated by the reference numeral 10. This drape may be constructed of fabric or any suitable material now used for the purpose and is folded back at the upper portion of the same to provide a hem 11. The portion of the drape having the hem 11 is formed with the desired pleats.

For forming the pleats a form 12 is employed which is constructed from buckram, crinoline, or some other suitable relatively stiff material which may be readily bent by creasing, scoring, or other-

wise. The blank from which the said form is constructed is shown in Fig. 5 and indicated by the reference numeral 13. This blank is rectangular in shape and has upper and lower edges 14 and 15 and lateral edges 16 and 17. The blank 13 is provided with three longitudinally extending scores 19, 20 and 21 which are equally spaced from one another and from the edges 16 and 17 and which are parallel to said edges. These scores divide the blank into four panels 22, 23, 24 and 25. The score 20 is constructed so that the reentrant angle of the bight 26 formed between the panels 23 and 24 is disposed on one side of the blank and the scores 19 and 21 are constructed so that the reentrant angles of the bights 27 and 127 formed between the panels 22 and 23 and the panels 24 and 25 lie on the opposite side of the blank. By means of this construction the panels may be folded up in accordion fashion as with the form 12 shown to the left of Fig. 3. Near the lowermost marginal portion of the blank 13 is punched a number of holes 28, 29, 30, 31, 32, 33, 34 and 35. The holes 28 and 29 are on panel 22, the holes 30 and 31 on panel 33, the holes 32 and 33 on panel 24, while the holes 34 and 35 are on panel 25. These holes are arranged in two horizontal rows, the holes 28, 30, 32 and 34 being in the upper row and the holes 29, 31, 33 and 35 being in the lower row. The holes 28 and 29 and the holes 34 and 35 are the same distance from the edges 16 and 17 of the blank while the holes 30, 31, 32 and 33 are the same distance from the score 20. When the panels of the form are folded together the holes in each row are brought into register.

In applying the form 12 to the drape the portion of the drape adjacent the bight 27 of the form is gathered into said bight and a wire stitch or staple 45 directed through the holes 28, 29, 30 and 31. This forms a bend 36 in the fabric of the drape received within the bight 27 and panels 37 and 38 lying along the panels 22 and 23 of the form 12. A fold 39 is thus formed in the material which is received between the panels 22 and 23. In a similar manner the material of the drape adjacent the bight 127 formed between panels 24 and 25 is gathered into said bight to form bends 40 and 41 in the material at the locality of the scores 20 and 21 and panels 42 and 43 and overlying the panels 24 and 25. A fold 44 is thus formed in the material which is received within the bight 127. Another wire stitch or staple 72 is placed through the holes 32, 33, 34 and 35 and through the material in between said holes thus holding the parts firmly in position. The disposition of the parts after attachment of the drape thereto is best shown in conjunction with the form indicated at 12 in Fig. 1.

In conjunction with the form 12 a clip 46 is employed. This clip is constructed of metal elongated in form and is provided with a channel 47 extending longitudinally thereof as indicated in Fig. 1. This channel forms a longitudinally extending recess 48 coextensive with the length of the clip. The said channel, however, falls short of the lateral marginal portions 49 and 50 of the clip which lie in a common plane. Formed in the channel 47 are four transverse slots 51, 52, 53 and 54. The slots 52 and 53 extend completely across the channel and are of appreciable width while the slots 51 and 54 are narrower and extend only partly across said channel. The marginal portions 49 and 50 adjacent the slots 52 and 53 are formed with depressions 55 which lie in continuation of the lowermost portions of the said slots. In the center of the channel 47 are

two openings 56 and 57 which serve a purpose to be presently described. These openings are arranged one above the other as best illustrated in Fig. 4.

After the form 12 has been attached to the drape the portions of the drape adjacent the edges 16 and 17 of said form are wrapped about said form to provide bends 58 and 59 at said edges and to form panels 60 and 61 overlying the outer surfaces of the panels 22 and 25. This construction provides folds 62 and 63 receiving within them the panels 22 and 25. Where the panels 60 and 61 meet the portions of the form 12 located at the scores 19 and 21 are brought together and further bent as indicated at 64 and 65 to form folds 66 and 67. These folds are received in the recess 48 of the clip 46. When in position pins 68 and 69 are passed through these folds and are received in the depressions 55. The pins 68 and 69 have bends 73 in the same which are normally arranged toward the drape and which facilitate insertion of the pins into the material at the folds 64 and 65. After insertion these pins are reversed to take the position shown in Fig. 3. When so disposed the material is drawn into the recess 48 and the head of the pin engaging the fabric of the drape or the clip 46 prevents rotation of the pin. Due to the resiliency of the fabric from which the drape is constructed and the resiliency of the form the pleats are formed by the folds 62, 42, and 63 which are drawn together as designated at 70 in Fig. 2 and which spread apart above and below said localities to give the pleat the desired appearance. Where the drape is constructed of heavy material the holes 52 and 53 are employed and the pins 68 and 69 inserted into said holes and rest on the fabric or on the marginal portions 49 and 50 of the clip 46 at the depressions 55. Where lighter material is used the holes 51 and 54 are employed and the pins rest on the edges of the channel 47 formed by said holes.

For supporting the drape, hooks 71 are employed which may be of the customary construction and which are hooked into either of the holes 56 or 57 of each mounting and which are further hooked about the rod or supporting structure for the drape.

The advantages of the invention are manifest. The drapes can be formed with "French" pleats in a fraction of the time heretofore employed. The forms and clips are simple to apply and can be fabricated at an economical cost. Whenever it becomes desirable the forms and clips may be quickly removed and the drape laundered in any desired fashion.

Changes in the specific form of the invention, as herein described, may be made within the scope of what is claimed without departing from the spirit of the invention.

Having described the invention, what is claimed as new and desired to be protected by Letters Patent is:

1. In drapery pleat construction, a drape, a form constructed from a sheet of bendable material having greater rigidity than the material of the drape and formed with spaced edges and bent alternately in opposite directions in accordion fashion along spaced lines extending generally in the same direction as said edges to form pairs of juxtaposed panels with reentrant angles therebetween facing forwardly of the drape and with said edges forming the lateral edges of the outer panels of the pairs of panels, said drape being folded at the bends of the form and having portions received within said reentrant

angles and overlying the forward surfaces of said panels, a fastener extending through each of said portions of the drape received within said angles and through the pairs of panels of the form providing the angles in which said portions are received to bring said portions of the drape in overlying contacting position, said drape having other portions folded back over the lateral edges of the outer panels and upon the rearwardly facing surfaces of the outer panels and concealing said fasteners and having bends at the rearward portions of said outer panels extending rearwardly of the portions of the drape received within said reentrant angles and said form to provide outwardly facing pleats in the drape and fastening means engaging said drape at said bends and holding the bends thereof in juxtaposition to envelope said form, said fasteners being disposed at a locality spaced from the upper end of the form to provide in the pleats gathers.

2. In drapery pleat construction, a drape, a form constructed from a sheet of bendable material having greater rigidity than the material of the drape and formed with spaced edges and bent alternately in opposite directions in accordion fashion along spaced lines extending generally in the same direction as said edges to form pairs of juxtaposed panels with reentrant angles therebetween facing forwardly of the drape and with said edges forming the lateral edges of the outer panels of the pairs of panels, said drape being folded at the bends of the form and having portions received within said reentrant angles and overlying the forward surfaces of said panels, a fastener extending through each of said portions of the drape received within said angles and through the pairs of panels of the form providing the angles in which said portions are received to bring said portions of the drape in overlying contacting position, said drape having other portions folded back over the lateral edges of the outer panels and upon the rearwardly facing surfaces of the outer panels and concealing said fasteners and having bends at the rearward portions of said outer panels extending rearwardly of the portions of the drape received within said reentrant angles and said form to provide outwardly facing pleats in the drape, a clip constructed of sheet material and overlying the last named bends of the drape, said clip having a transverse slot therein extending across said bends and marginal portions outwardly therefrom, and a pin received in said slot and extending through the portions of the drape traversed by said slot and being free from said form, said

pin engaging the marginal portion of the clip and holding the bends of the drape in juxtaposition to envelope the form, said fasteners being disposed at a locality spaced from the upper end of the form to provide in the pleats gathers.

3. In drapery pleat construction, a drape, a form constructed from a rectangular sheet of bendable material having greater rigidity than the material of the drape and bent alternately in opposite directions in accordion fashion along three equally spaced lines parallel with two of the edges of the sheet to form two pairs of juxtaposed panels with reentrant angles therebetween facing forwardly of the drape and with the denoted edges of the sheet forming the lateral edges of the outer panels of the pairs of panels, said drape being folded at the bends of the form and having portions received within said reentrant angles and overlying the forward surfaces of said panels, a fastener extending through each of said portions of the drape received within said angles and through the pairs of panels of the form providing the angles in which said portions are received, to bring said portion of the drape in overlying contacting position, said drape having other portions folded back over the lateral edges of the outer panels and upon the rearwardly facing surfaces of the outer panels to conceal the fasteners and having bends at the rearward portions of the outer panels extending rearwardly of the portions of the drape received within said reentrant angles and said form to provide outwardly facing pleats in the drape and fastening means engaging said drape at said bends and free from said form and holding the bends thereof in juxtaposition to envelope the form, said fastener being disposed at a locality spaced from the upper end of the form to provide in the pleats gathers.
